UNITED STATES PATENT OFFICE.

JOHN W. COSGROVE, OF MEDFORD, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

Application filed October 2, 1920. Serial No. 414,281.

This invention relates to fastening inserting machines and is illustrated herein as embodied in a fastening inserting machine which prepares the work for the insertion of 5 other fastenings.

Insoles utilized in the manufacture of certain types of shoes are provided with lips or ribs which stand up from the body of the insole and serve as means for the attachment 10 of other parts of the shoe, as for instance, of the upper or of the upper and welt. The rear ends of such an upstanding rib or lip are located in proximity to the breast line of the heel, and for some distance forward 15 of this line in the shank of the shoe the upper has a very considerable tendency to pull the lip or rib outwardly causing a fullness or slack in the upper of the completed shoe. One of the methods by which the difficulties 20 above mentioned are overcome involves the attachment of the rear ends of the lip or rib to the body of the insole by the insertion of fastenings. As a preliminary step in the operation it is necessary to bend the rear end 25 of the lip or rib inwardly or backwardly against the body of the insole so that a fastening may be inserted and properly clinched. In many cases the lip or rib resists bending to such an extent as to make 30 it a difficult operation to perform by hand or by any machine heretofore known.

In view of the foregoing, it is an object 35 of this invention to provide a fastening inserting machine having improved means for positioning the work or parts of the work relatively to other parts preparatory to the insertion of a fastening or fastenings or preparatory to securing work parts in the relation in which they are positioned by said 40 means, which machine will be adapted for performing the rib-bending and attaching operation above referred to.

To this end and in accordance with a feature of the invention, the illustrated fastening inserting machine is characterized by 45 the provision of movable means for bending the rear portions of the lips or ribs of insoles back against the bodies of the insoles, and holding the lips or ribs thus bent during the 50 insertion of fastenings which permanently hold the end portions of the ribs in that position. It should be understood, however, that in various respects, the invention is not restricted to embodiment in the illustrated

type of machine, or to use in performing 55 the particular operation just referred to.

In accordance with a further feature of the invention, the illustrated rib-bending means is operated to bend the rib of an insole back against the body portion of the 60 insole, preliminarily to securing the rib in that position, by movement transversely of the surface of the insole.

In accordance with another feature of the invention, the illustrated machine is provided with gripping or clamping means intermittently operable to clamp the rib of an insole which has been bent back, as above stated, against the body of the insole, and to hold it so clamped during the insertion of a 65 fastening therein. Preferably, and as illustrated, the fastening inserted is a fine wire staple, which is inserted through the insole from its foot-engaging surface, and which, after passing through the rib, is clinched 70 upon the surface of the insole.

In the illustrative machine, the anvil which clinches the fastening driven through the insole by the driver operates by a hammer blow to ensure the completion of the 75 bending of the rib or lip which has been turned over by the bending slide and to hold the rib during the fastening insertion and clinching operation.

Other features of the invention and other 80 combinations of parts will be described in the detailed specification and pointed out in the appended claims.

In the drawings:—

Figure 1 is a view in side elevation and 85 partly in section of a staple fastening inserting machine embodying the invention;

Fig. 2 is a detail view in perspective showing the insole clamping and rib bending devices; and

Fig. 3 is a section along the line 3—3, extended, in Fig. 1 and looking toward the left in said figure.

The invention is illustrated as embodied 90 in a fastening inserting machine of the general type disclosed in United States Letters Patent No. 1,164,784, granted December 21, 1915, on the application of J. W. Cosgrove. Referring to the drawings, the 95 reference character 4 designates the outside former which operates to bend the staple wire over the inside former 6, the latter being reciprocable vertically into and out

of operative relation with respect to the outside former. After the staple has been formed it is carried forwardly to the right in Figure 1 by a continued movement of the outside former and subsequently driven by the driver 8 which operates in a groove in the outside former in accordance with a construction and arrangement that is very common in machines for inserting staple fastenings. For operating the driver there is preferably provided a driver bar 10 having a rack 12 which is constantly in mesh with a segment rack 14 on a lever 16 pivoted at 18 and carrying a cam roll 20 which runs in a cam track in a cam member 22. Conveniently, the outside former is driven by a similar arrangement of driving parts consisting of a rack bar 24 secured to or integral with the former 4 and arranged to be constantly in mesh with a segment rack 26 on a lever 28 pivoted at 30 in the frame of the machine and carrying a roll 32 which moves along a cam path in the cam member 22. For clinching the fastenings as they are driven through the work, there is provided an anvil member 34 securely attached to the anvil carrier 36 which is slidable along guideways provided upon the member 38 fixedly secured to the forward part of the machine frame. While the machine is at rest the anvil is spaced from the outlet of the fastening guiding nozzle and is operated to clamp the work against the nozzle and to clinch the fastening while the driver is forcing the same through the work. For moving the anvil in properly timed relation to the outside former and to the driver, means is provided for reciprocating the anvil carrier 36, the said means comprising preferably a lever 40 pivoted at 42 to the machine frame and having its upper end connected by an extensible link 44 to an arm 46 projecting from the lever 28. It will be noted that the link 44 is pivotally connected at 48 to the lever 40 and also pivotally connected to the arm 46, a plurality of such connecting points being provided on the arm 46 so as to provide for adjustments in the connections by which means the lever 40 may be given operative movement of greater or less extent. Pivoted to the lever 40 at 52 is a link 54 which extends through the anvil carrier 36 and has a spring 56 surrounding the link between an outer surface of the anvil carrier and a washer 58 secured to the end of the link so that the anvil carrier is pulled yieldingly in the direction to force the anvil against the work during clinching operations. The machine thus far described is substantially like that shown in said Letters Patent and for a more complete description of the operative parts of the machine reference should be had to said Letters Patent.

Secured to the machine frame in place of

the nozzle shown in said Letters Patent there is provided a nozzle member 60 having a passageway therethrough at 62 for the outside former and for the driver 8 which moves in the former between the dotted lines indicated at 64 and the solid lines at 66, the driver passing through an inverted T-shaped opening in the flat-ended nozzle member 60 (Fig. 3). Conveniently, the nozzle member 60 has an upward extension 68 upon which is pivoted two gripper or clamping members 70, light springs 72 (Fig. 1) being provided in the extension 68 to hold the gripper members 70 normally spaced from the end surface of the nozzle 60, the said gripper members being movable about the pivot 74 to clamp the work against the end face of the nozzle which it will be seen serves as a presser member or abutment against which the work is held while the positioning and fastening inserting operations are performed. As illustrated the gripper members are operated to clamp the work by means of spring pressed plungers 76 slidably mounted in sockets 78 in the anvil carrier 36 and held yieldingly in operative position by means of springs 80, one in each socket, adjustably tensioned through lock nuts or other adjustable members 82, at one end of each plunger 76. It will be clear that as the anvil carrier 36 is moved to the left in Figure 1, the plungers 76, of which there are two, will be caused to engage each with its respective clamp member 70 to force the latter firmly into contact with the work which has previously been positioned by the operator in proper relation to the end face of the nozzle member 60. For positioning the work or parts thereof with respect to each other, more specifically for bending the upstanding rib of an insole down over against the body thereof, there is provided a rib bender illustrated as a slide member 84, which is mounted in guideways in side plates 85 bolted to the hollow head, and which is bifurcated at its upper end, as shown in Figures 2 and 3, to embrace the anvil carrier support 38 and the link member 54 and to provide spaced attaching points for the bell crank 86 which serves as the immediate operating means for the slide. Preferably, the lower end of the bending slide 84 is also bifurcated to straddle the anvil 34 and engage the rib of the insole on either side of the anvil to bend it downwardly into contact with the body of the insole prior to the engagement of the anvil therewith during fastening inserting and clinching operations. It will be understood that the staple fastening is driven through the insole and rib and clinched against the face of the latter. There is no danger therefore of injury to the foot of the wearer since the staple ends are on the opposite side of the insole. Con-

veniently the bell crank 86 is attached to the slide member 84, for lifting the same, through links 88 which are in the shape of hooks and permit of ready detachment of the slide from its operating means. It will be noted that the ends of the arms of the bell crank rest directly upon the upper end surfaces of the arms of the bender 84 and thus force is applied directly from the bell 5 crank to the bending slide 84 in giving the latter its operative stroke. Preferably the bell crank 86 and the bending slide 84 are operated from the lever 40 which controls the movements of the anvil and anvil carrier, an operative connection being provided 10 between the bell crank 86 and the lever 40 through an extensible link 90 pivoted to the bell crank at 92 and provided with a slot 94 slidable upon the pivot pin 48 whereby 15 a lost motion connection is provided, the arrangement being such that operation of the lever 40 will move the anvil through the greater part of the distance it has to travel in approaching the work before the 20 bending slide 84 is operated. In Fig. 1 the anvil is shown just about to engage the insole, prior to which the bending slide moves downwardly to fold the outstanding lip or rib of the insole inwardly from the edge 25 and down against the body thereof where it is clamped at the point of fastening insertion by the anvil, as shown in Fig. 2, and held during the insertion of the fastening which is clenched against the end 30 surface of the anvil. The anvil operates with a hammer blow to ensure the complete bending of the rib or lip and to clinch the fastening securely. At the end of the cycle 35 of operations, the anvil moves away from the nozzle and the bending slide 84 is withdrawn upwardly, as the lever 40 moves to the right in Fig. 1, the insole being released 40 from the clamping members 70 upon retraction of the anvil carrier with the plungers 76 carried thereby. The insole is then 45 rotated to project the heel end in a direction opposite to that shown in Fig. 2, and the other edge of the insole upward to present the rear end portion of the other 50 lip or upstanding rib just above the line of fastening insertion which may be gaged by a shoulder on the nozzle extension 68 or located with reference to the gripper or 55 clamping members 70. With the insole thus reversed that is, with the heel end thereof pointing to the left in Fig. 2, the right fork of the bending slide 84 may be depended upon to effect the bending of the rib down 60 upon the insole so as to insert the fastening near the end of the rib. Operation of the machine results as before in bending the rib down upon the body of the insole and in inserting a fastening to hold it in its 65 shaped or bended condition. In a preferred construction a gage 96 is provided for lo- cating the insole with respect to the fastening inserting means. As shown, the gage 96 is a plate dovetailed into a bifurcated portion of the nozzle extension 68. For adjustment of the gage, the bolt 74 is turned 70 in one direction to release the arms of the extension 68 whereupon the gage plate 96 may be moved upwardly or downwardly so as to adjust it in accordance with the width of the feather on the insole. After the gage 75 plate has been moved to the desired position, the bolt 74 is turned in the opposite direction to cause the arms of the extension 68 to grip or clamp the plate 96, holding it firmly in adjusted position. As before 80 pointed out extensions of the bolt 74 support the gripper or clamping members 70 for loose pivotal movement. Since the insole is firmly clamped against the flat end of the nozzle prior to the operation of the bending slide 84, the work is held securely 85 in position during the bending operation and insole ribs which have heretofore been the cause of considerable trouble because of stiffness, are bent easily into proper position 90 and securely attached in the desired relation to the body of the insole.

Having thus described the invention, what is claimed as new and desired to be secured by Letters Patent of the United States is:—

1. In a machine of the character described, a backing for work, means movable for clamping work against said backing, work positioning means movable in a plane at right angles to the plane along which the clamping force is applied, work positioning means operating along a plane angularly related to the plane of the first mentioned positioning means, and means for securing parts of the work positioned by said positioning means together. 100
2. In a machine of the character described, a backing for work, stationary means for locating the work, means comprising bending members restricted to sliding movement at right angles to each other and automatically operable to position portions of the work relatively to each other, and means for inserting a fastening to hold the work while 105 it is held by the positioning means. 110
3. In a machine of the character described, fastening inserting mechanism comprising a nozzle and an anvil relatively movable to insert and clinch fastenings in work, means for clamping the work against the nozzle, and means controlled by the fastening inserting mechanism for positioning portions of the work relatively to each other previous to the insertion of a fastening. 115
4. In a machine of the character described, fastening inserting mechanism comprising a nozzle portion and an anvil relatively movable toward and from each other for inserting and clinching fastenings, means for 120
- 65
- 125
- 130

- clamping the work against the nozzle, and means movable along a path angularly related to the relative approaching movement of the anvil and nozzle for positioning portions of the work relatively to each other prior to the insertion of a fastening.
5. In a machine of the character described, fastening inserting mechanism, means for clamping an insole against the fastening inserting mechanism, and movable means for bending the upstanding rib of the insole at the rear portion thereof inwardly away from the edge of the insole previous to the insertion of a fastening.
10. In a machine of the character described, fastening inserting means comprising a nozzle, means for clamping an insole against the nozzle, an anvil member for controlling the clamping means and for clinching the fastening as the same is inserted into the work, and means for bending the rib of the insole inwardly away from the edge thereof prior to the insertion of a fastening.
15. In a machine of the character described, fastening inserting mechanism comprising a nozzle portion, an anvil movable toward and from the nozzle to clinch fastenings inserted through an insole, means for clamping the work arranged to be controlled by the anvil member, and a slidable member for bending the rib of the insole inwardly away from the edge thereof prior to the insertion of a fastening.
20. In a machine of the character described, fastening inserting mechanism comprising a nozzle, means for supporting an insole, a slide movable in a plane parallel to that of the insole for bending the rib or lip of the insole inwardly from the edge thereof, and a member movable at right angles to said slide for striking a hammer blow on the bent rib to insure completion of the bending operation.
25. In a machine of the character described, means for inserting a fastening into the rib of an insole, and means movable for bending the rib of the insole at the rear portion thereof inwardly away from the edge of the insole prior to the insertion of a fastening.
30. In a machine of the character described, fastening inserting mechanism comprising a flat-ended nozzle portion, means for clamping an insole against the flat portion of the nozzle, and a slide member movable in a plane parallel to that of the insole to engage the rib of the insole at the rear portion thereof to bend it inwardly away from the edge of the insole prior to the insertion of a fastening.
35. In a machine of the character described, a fastening inserting mechanism comprising a nozzle having a flat end portion, a gage for positioning an insole on said end portion, a pivoted gripper member for clamping the insole against said flat portion of the nozzle, an anvil member for clinching a fastening driven through the insole, and a member
- operative to bend the rear portion of the rib of the insole over against the body thereof prior to the insertion of a fastening.
12. In a machine of the character described, fastening inserting mechanism comprising a flat-ended nozzle, an anvil movable toward and from the nozzle to clinch fastenings driven through an insole, a clamping member operated by the anvil member for holding the insole against the nozzle, and a slide having operative connections with the fastening inserting mechanism for bending the rear portion of the rib of the insole inwardly away from the edge thereof prior to the insertion of a fastening.
13. In a machine of the character described, fastening inserting mechanism comprising a nozzle and an anvil member relatively movable toward and from each other in fastening inserting operations, a member for clamping an insole against the nozzle controlled by the relative movement of the nozzle and anvil member, and a member slideable across the face of the insole clamped against the nozzle and operative to bend the rear portion of the rib of the insole down against the body thereof prior to the insertion of a fastening.
14. In a machine of the character described, fastening inserting mechanism comprising a nozzle, an anvil movable toward and from the nozzle during fastening inserting operations for clamping an insole against the nozzle during the clinching of fastenings, a member slideable in a plane closely adjacent to the plane of the insole clamped against the nozzle, power means for operating the inserting mechanism to insert a fastening through the insole, and connections between said power means and the slideable member for operating the latter to bend the rib of the insole inwardly away from the edge of the insole prior to the insertion of a fastening.
15. In a machine of the character described, a backing for an insole, means reciprocal for clamping the insole against said backing, and means movable after each reciprocation of the clamping means and in a plane parallel to that of the insole for bending the rib of the insole over against the body thereof.
16. In a machine of the character described, a backing for an insole, means comprising a bifurcated member for clamping an insole against the backing, and a slide movable through the bifurcation of the clamp member and in a plane parallel to that of the insole for bending the rib of the insole inwardly from the edge thereof.
17. In a machine of the character described, a backing for an insole, means for clamping an insole against the backing, a slide movable in a plane parallel to that of the insole for bending the rib of the insole

- inwardly from the edge of the insole, and a member movable at right angles to said slide for co-operation with the latter in applying a bending pressure on the rib.
- 5 18. In a machine of the character described, means for holding an insole, and means movable in a plane parallel to that of the insole and also along a path angularly related thereto for bending the rib of the insole inwardly away from the edge thereof.
- 10 19. In a machine of the character described, a backing for an insole, a clamp member intermittently operative for clamping an insole against the backing, and a slide member movable in a plane parallel to that of the insole to engage the rib of the insole and bend it over toward the body thereof.
- 15 20. In a machine of the character described, a backing for an insole, a clamp member intermittently operative for clamping an insole against the backing, a slide member movable in a plane parallel to that of the insole to engage the rib of the insole and bend it over toward the body of the insole, and an anvil member for co-operation with the slide to apply additional pressure on the bent over rib.
- 20 21. In a machine of the character described, a backing for an insole, means movable for clamping the insole against the backing, and a fastening inserting mechanism including an anvil operative to bend a rib of the insole down against the body thereof and to clinch a fastening driven to hold the rib in its bent-over position.
- 25 22. In a machine of the character described, a backing and a gage unobstructed and accessible for the positioning of an insole having a rib, means movable transversely of the rib-bearing surface of the insole arranged thereby to bend the rear end portion of the rib of the insole inwardly from the edge of the insole, and means for inserting a staple fastening to secure the rib in its bent-over position.
- 30 23. In a machine of the character described, the combination of supporting means and a rib bending device initially arranged to permit an insole to be placed upon the supporting means, staple inserting mechanism, and means for operating the inserting mechanism and the rib bending device to press the rib inwardly against the body portion of the insole and hold it under pressure while the fastening is inserted.
- 35 24. In a machine of the character described, means for supporting a welt insole having a sewing rib, rib bending means including means to crowd the rear end portion of the sewing rib inwardly from the edge of the insole and bend it over upon the body of the insole, and staple inserting mechanism operative to insert a staple to hold the rib in its bent-over relation on the body of the insole.
- 40 25. In a machine of the character described, a plurality of members restricted to sliding movement at a right angle to each other to operate upon a piece of work in succession to position a part of the piece of work with respect to another part thereof, and means for securing the parts of the work together.
- 45 26. In a machine of the character described, means intermittently operative to clamp a piece of work to hold it in operative position, and two members movable at a right angle to each other, one member being operative to bend a part of the work over against the body portion thereof and the other member serving as a pressure to insure bending of the part into the position in which it is finally secured to the body portion.
- 50 27. In a machine of the character described, a backing for an insole to support the same, a slide movable in a plane parallel to that of the insole for bending a rib on the insole over against the body portion thereof, and means for inserting a fastening to secure the rib in bent-over position.
- 55 28. A fastening inserting machine having an abutment arranged to receive an insole, a clamp arranged to force an insole against said abutment, a bender movable transversely across the surface of the insole arranged by its transverse movement to bend the rear end of the rib of the insole back toward the surface of the insole, and means for inserting a fastening to secure the end of the rib of the insole to the body of the insole in said bent relation.
- 60 29. A fastening inserting machine having, in combination, an abutment arranged to receive an insole, means for clamping an insole to said abutment, a bender movable transversely of the surface of the insole to bend the end of the rib of the insole back toward the surface of the insole, means movable substantially at right angles to the surface of the insole to force the end of the rib firmly against the surface of the insole, and means for inserting a staple to secure the rib to the insole while the rib and the insole are thus held.
- 65 30. In testimony whereof I have signed my name to this specification.

JOHN W. COSGROVE.

Certificate of Correction.

Patent No. 1,642,014.

Granted September 13, 1927, to

JOHN W. COSGROVE.

It is hereby certified that error appears in the printed specification of the above-numbered patent requiring correction as follows: Page 5, line 81, claim 26, for the word "pressure" read *presser*; and that the said Letters Patent should be read with this correction therein that the same may conform to the record of the case in the Patent Office.

Signed and sealed this 6th day of December, A. D. 1927.

[SEAL.]

M. J. MOORE,
Acting Commissioner of Patents.
